ABSTRACT

The invention relates to systems for transferring molten metal from one structure to another. Aspects of the invention include a transfer chamber constructed inside of or next to a vessel used to retain molten metal. The transfer chamber is in fluid communication with the vessel so molten metal from the vessel can enter the transfer chamber. A powered device, which may be inside of the transfer chamber, moves molten metal upward and out of the transfer chamber and preferably into a structure outside of the vessel, such as another vessel or a launder.

MOLTEN METAL TRANSFER VESSEL AND METHOD OF CONSTRUCTION

CROSS-REFERENCE TO RELATED APPLICATIONS

This application is a continuation-in-part of, and claims priority under 35 U.S.C. §§119 and 120 to, U.S. patent application Ser. No. 13/725,383, filed on Dec. 21, 2012, currently pending, by Paul V. Cooper, which is a divisional of, and claims priority to U.S. patent application Ser. No. 11/766,617 (Now U.S. Pat. No. 8,337,746), filed on Jun. 21, 2007, by Paul V. Cooper, the disclosure(s) of which that is not inconsistent with the present disclosure is incorporated herein by reference. This application incorporates by reference the portions of U.S. patent application Ser. No. 13/797,616 (Now U.S. Pat. No. 9,017,597), filed on Mar. 12, 2013, by Paul V. Cooper, that are not inconsistent with this disclosure.

FIELD OF THE INVENTION

The invention relates to a system for moving molten metal out of a vessel, and components used in such a system.

BACKGROUND OF THE INVENTION

As used herein, the term "molten metal" means any metal or combination of metals in liquid form, such as aluminum, copper, iron, zinc and alloys thereof. The term "gas" means any gas or combination of gases, including argon, nitrogen, chlorine, fluorine, freon, and helium, that are released into molten metal.

Known molten-metal pumps include a pump base (also called a housing or casing), one or more inlets (an inlet being an opening in the housing to allow molten metal to enter a pump chamber), a pump chamber, which is an open area formed within the housing, and a discharge, which is a channel or conduit of any structure or type communicating with the pump chamber (in an axial pump the chamber and discharge may be the same structure or different areas of the same structure) leading from the pump chamber to an outlet, which is an opening formed in the exterior of the housing through which molten metal exits the casing. An impeller, also called a rotor, is mounted in the pump chamber and is connected to a drive system. The drive system is typically an impeller shaft connected to one end of a drive shaft, the other end of the drive shaft being connected to a motor. Often, the impeller shaft is comprised of graphite, the motor shaft is comprised of steel, and the two are connected by a coupling. As the motor turns the drive shaft, the drive shaft turns the impeller and the impeller pushes molten metal out of the pump chamber, through the discharge, out of the outlet and into the molten metal bath. Most molten metal pumps are gravity fed, wherein gravity forces molten metal through the inlet and into the pump chamber as the impeller pushes molten metal out of the pump chamber.

A number of submersible pumps used to pump molten metal (referred to herein as molten metal pumps) are known in the art. For example, U.S. Pat. No. 2,948,524 to Sweeney et al., U.S. Pat. No. 4,169,584 to Mangalick, U.S. Pat. No. 5,203,681 to Cooper, U.S. Pat. No. 6,093,000 to Cooper and U.S. Pat. No. 6,123,523 to Cooper, and U.S. Pat. No. 6,303,074 to Cooper, all disclose molten metal pumps. The disclosures of the patents to Cooper noted above are incorporated herein by reference. The term submersible means that when the pump is in use, its base is at least partially submerged in a bath of molten metal.

Three basic types of pumps for pumping molten metal, such as molten aluminum, are utilized: circulation pumps, transfer pumps and gas-release pumps. Circulation pumps are used to circulate the molten metal within a bath, thereby generally equalizing the temperature of the molten metal. Most often, circulation pumps are used in a reveratory furnace having an external well. The well is usually an extension of the charging well where scrap metal is charged (i.e., added).

Transfer pumps are generally used to transfer molten metal from the external well of a reveratory furnace to a different location such as a ladle or another furnace.

Gas-release pumps, such as gas-injection pumps, circulate molten metal while introducing a gas into the molten metal. In the purification of molten metals, particularly aluminum, it is frequently desired to remove dissolved gases such as hydrogen, or dissolved metals, such as magnesium. As is known by those skilled in the art, the removing of dissolved gas is known as "degassing" while the removal of magnesium is known as "demagging." Gas-release pumps may be used for either of these purposes or for any other application for which it is desirable to introduce gas into molten metal.

Gas-release pumps generally include a gas-transfer conduit having a first end that is connected to a gas source and a second end submerged in the molten metal bath. Gas is introduced into the first end and is released from the second end into the molten metal. The gas may be released downstream of the pump chamber into either the pump discharge or a metal-transfer conduit extending from the discharge, or into a stream of molten metal exiting either the discharge or the metal-transfer conduit. Alternatively, gas may be released into the pump chamber or upstream of the pump chamber at a position where molten metal enters the pump chamber.

Generally, a degasser (also called a rotary degasser) includes (1) an impeller shaft having a first end, a second end and a passage for transferring gas, (2) an impeller, and (3) a drive source for rotating the impeller shaft and the impeller. The first end of the impeller shaft is connected to the drive source and to a gas source and the second end is connected to the connector of the impeller. Examples of rotary degassers are disclosed in U.S. Pat. No. 4,898,367 entitled "Dispersing Gas Into Molten Metal," U.S. Pat. No. 5,678,807 entitled "Rotary Degassers," and U.S. Pat. No. 6,689,310 to Cooper entitled "Molten Metal Degassing Device and Impellers Therefore," filed May 12, 2000, the respective disclosures of which are incorporated herein by reference.

The materials forming the components that contact the molten metal bath should remain relatively stable in the bath. Structural refractory materials, such as graphite or ceramics, that are resistant to disintegration by corrosive attack from the molten metal may be used. As used herein "ceramics" or "ceramic" refers to any oxidized metal (including silicon) or carbon-based material, excluding graphite, capable of being used in the environment of a molten metal bath. "Graphite" means any type of graphite, whether or not chemically treated. Graphite is particularly suitable for being formed into pump components because it is (a) soft and relatively easy to machine, (b) not as brittle as ceramics and less prone to breakage, and (c) less expensive than ceramics.

Generally a scrap melter includes an impeller affixed to an end of a drive shaft, and a drive source attached to the other end of the drive shaft for rotating the shaft and the impeller. The movement of the impeller draws molten metal and scrap metal downward into the molten metal bath in order to melt the scrap. A circulation pump is preferably used in conjunction with the scrap melter to circulate the molten metal in order to maintain a relatively constant temperature within the

molten metal. Scrap melters are disclosed in U.S. Pat. No. 4,598,899 to Cooper, U.S. patent application Ser. No. 09/649,190 to Cooper, filed Aug. 28, 2000, and U.S. Pat. No. 4,930,986 to Cooper, the respective disclosures of which are incorporated herein by reference.

Molten metal transfer pumps have been used, among other things, to transfer molten aluminum from a well to a ladle or launder, wherein the launder normally directs the molten aluminum into a ladle or into molds where it is cast into solid, usable pieces, such as ingots. The launder is essentially a trough, channel or conduit outside of the reverberatory furnace. A ladle is a large vessel into which molten metal is poured from the furnace. After molten metal is placed into the ladle, the ladle is transported from the furnace area to another part of the facility where the molten metal inside the ladle is poured into other vessels, such as smaller holders or molds. A ladle is typically filled in two ways. First, the ladle may be filled by utilizing a transfer pump positioned in the furnace to pump molten metal out of the furnace, through a metal-transfer conduit and over the furnace wall, into the ladle or other vessel or structure. Second, the ladle may be filled by transferring molten metal from a hole (called a tap-out hole) located at or near the bottom of the furnace and into the ladle. The tap-out hole is typically a tapered hole or opening, usually about 1"-4" in diameter that receives a tapered plug called a "tap-out plug." The plug is removed from the tap-out hole to allow molten metal to drain from the furnace, and is inserted into the tap-out hole to stop the flow of molten metal out of the furnace.

There are problems with each of these known methods. Referring to filling a ladle utilizing a transfer pump, there is splashing (or turbulence) of the molten metal exiting the transfer pump and entering the ladle. This turbulence causes the molten metal to interact more with the air than would a smooth flow of molten metal pouring into the ladle. The interaction with the air leads to the formation of dross within the ladle and splashing also creates a safety hazard because persons working near the ladle could be hit with molten metal. Further, there are problems inherent with the use of most transfer pumps. For example, the transfer pump can develop a blockage in the riser, which is an extension of the pump discharge that extends out of the molten metal bath in order to pump molten metal from one structure into another. The blockage blocks the flow of molten metal through the pump and essentially causes a failure of the system. When such a blockage occurs the transfer pump must be removed from the furnace and the riser tube must be removed from the transfer pump and replaced. This causes hours of expensive downtime. A transfer pump also has associated piping attached to the riser to direct molten metal from the vessel containing the transfer pump into another vessel or structure. The piping is typically made of steel with an internal liner. The piping can be between 1 and 50 feet in length or even longer. The molten metal in the piping can also solidify causing failure of the system and downtime associated with replacing the piping.

If a tap-out hole is used to drain molten metal from a furnace a depression may be formed in the factory floor or other surface on which the furnace rests, and the ladle can preferably be positioned in the depression so it is lower than the tap-out hole, or the furnace may be elevated above the floor so the tap-out hole is above the ladle. Either method can be used to enable molten metal to flow using gravity from the tap-out hole into the ladle.

Use of a tap-out hole at the bottom of a furnace can lead to problems. First, when the tap-out plug is removed molten metal can splash or splatter causing a safety problem. This is

particularly true if the level of molten metal in the furnace is relatively high which leads to a relatively high pressure pushing molten metal out of the tap-out hole. There is also a safety problem when the tap-out plug is reinserted into the tap-out hole because molten metal can splatter or splash onto personnel during this process. Further, after the tap-out hole is plugged, it can still leak. The leak may ultimately cause a fire, lead to physical harm of a person and/or the loss of a large amount of molten metal from the furnace that must then be cleaned up, or the leak and subsequent solidifying of the molten metal may lead to loss of the entire furnace.

Another problem with tap-out holes is that the molten metal at the bottom of the furnace can harden if not properly circulated thereby blocking the tap-out hole or the tap-out hole can be blocked by a piece of dross in the molten metal.

A launder may be used to pass molten metal from the furnace and into a ladle and/or into molds, such as molds for making ingots of cast aluminum. Several die cast machines, robots, and/or human workers may draw molten metal from the launder through openings (sometimes called plug taps). The launder may be of any dimension or shape. For example, it may be one to four feet in length, or as long as 100 feet in length. The launder is usually sloped gently, for example, it may be sloped downward at a slope of approximately $\frac{1}{8}$ inch per each ten feet in length, in order to use gravity to direct the flow of molten metal out of the launder, either towards or away from the furnace, to drain all or part of the molten metal from the launder once the pump supplying molten metal to the launder is shut off. In use, a typical launder includes molten aluminum at a depth of approximately 1-10."

Whether feeding a ladle, launder or other structure or device utilizing a transfer pump, the pump is turned off and on according to when more molten metal is needed. This can be done manually or automatically. If done automatically, the pump may turn on when the molten metal in the ladle or launder is below a certain amount, which can be measured in any manner, such as by the level of molten metal in the launder or level or weight of molten metal in a ladle. A switch activates the transfer pump, which then pumps molten metal from the pump well, up through the transfer pump riser, and into the ladle or launder. The pump is turned off when the molten metal reaches a given amount in a given structure, such as a ladle or launder. This system suffers from the problems previously described when using transfer pumps. Further, when a transfer pump is utilized it must generally operate at a high speed (RPM) in order to generate enough pressure to push molten metal upward through the riser and into the ladle or launder. Therefore, there can be lags wherein there is no or too little molten metal exiting the transfer pump riser and/or the ladle or launder could be over filled because of a lag between detection of the desired amount having been reached, the transfer pump being shut off, and the cessation of molten metal exiting the transfer pump.

Furthermore, there are passive systems wherein molten metal is transferred from a vessel to another by the flow into the vessel causing the level in the vessel to rise to the point at which it reaches an output port, which is any opening that permits molten metal to exit the vessel. The problem with such a system is that thousands of pounds of molten metal can remain in the vessel, and the tap-out plug must be removed to drain it. When molten metal is drained using a tap-out plug, the molten metal fills another vessel, such as a sow mold, on the factory floor. First, turbulence is created when the molten metal pours from the tap-out plug opening and into such a vessel. This can cause dross to form and negate any degassing that had previously been done. Second, the vessel into which

the molten metal is drained must then be moved and manipulated to remove molten metal from it prior to the molten metal hardening.

Thus, known methods of transferring molten metal from one vessel to another can result in thousands of pounds of a molten aluminum alloy left in the vessel, which could then harden. Or, the molten metal must be removed by utilizing a tap-out plug as described above.

It is preferred that a system having a transfer chamber according to the invention is more positively controlled than either: (1) A passive system, wherein molten metal flows into one side of a vessel and, as the level increases inside of the vessel, the level reaches a point at which the molten metal flows out of an outlet on the opposite side. Such a vessel may be tilted or have an angled inner bottom surface to help cause molten metal to flow towards the side that has the outlet. (2) A system utilizing a molten-metal transfer pump, because of the inherent problems with transfer pumps, which are generally described in this Background section.

Furthermore, launders into which molten metal exiting a vessel might flow have been angled downwards from the outlet of the vessel so that gravity helps drain the molten metal out of the launder. This was often necessary because launders were typically used in conjunction with tap-out plugs at the bottom of a vessel, and tap-out plugs are dimensionally relatively small, plus they have the pressure of the molten metal in the vessel behind them. Thus, molten metal in a launder could not flow backward into a tap-out plug. The problem with such a launder is that when exposed to the air, molten metal oxidizes and forms dross, which in a launder appears as a semi-solid or solid skin on the surface of the molten metal. When the launder is angled downwards, the dross, or skin, is usually pulled into the molten metal flow and into whatever downstream vessel is being filled. This creates contamination in the finished product.

SUMMARY OF THE INVENTION

The invention relates to systems and methods for transferring molten metal from one structure to another. Aspects of the invention include a transfer chamber constructed inside of or next to a vessel used to retain molten metal. The transfer chamber is in fluid communication with the vessel so molten metal from the vessel can enter the transfer chamber. In certain embodiments, inside of the transfer chamber is a powered device that moves molten metal upward and out of the transfer chamber and preferably into a structure outside of the vessel, such as another vessel or a launder.

In one embodiment, the powered device is a type of molten metal pump designed to work in the transfer chamber. The pump includes a motor and a drive shaft connected to a rotor. The pump may or may not include a pump base or support posts. The rotor is designed to drive molten metal upwards through an enclosed section of the transfer chamber, and fits into the transfer chamber in such a manner as to utilize part of the transfer chamber structure as a pump chamber to create the necessary pressure to move molten metal upwards as the rotor rotates. As the system is utilized, it moves molten metal upward through the transfer structure where it exits through an outlet.

A key advantage of the present system is that the amount of molten metal entering the launder, and the level in the launder, can remain constant regardless of the amount of or level of molten metal entering the transfer chamber with prior art systems, the metal level in the transfer chamber rises and falls and can affect the molten metal level in the launder. Alterna-

tively, the molten metal can be removed from the vessel utilizing a tap-out plug, which is associated with the problems previously described.

The system may be used in combination with a circulation or gas-release (also called a gas-injection) pump that moves molten metal in the vessel towards the transfer structure. Alternatively, a circulation or gas-release pump may be used with or without the pump in the transfer chamber, in which case the pump may be utilized with a wall that separates the vessel into two or more sections with the circulation pump in one of the sections, and the transfer chamber in another section. There would then be an opening in the wall in communication with the pump discharge. As the pump operates it would move molten metal through the opening in the wall and into the section of the vessel containing the transfer chamber. The molten metal level in that section would then rise until it exits an outlet in communication with the transfer chamber.

In an alternate embodiment, a molten metal pump is utilized that has a pump base and a riser tube that directs molten metal upward into the enclosed structure (or uptake section) of the transfer chamber, wherein the pressure generated by the pump pushes the molten metal upward through the riser tube, through the enclosed structure and out of an outlet in communication with the transfer chamber.

Also described herein is a transfer chamber and a rotor that can be used in the practice of the invention.

The present invention includes a system for transferring molten metal into a ladle or launder and comprises at least (1) a vessel for retaining molten metal, (2) a dividing wall (or overflow wall) within the vessel, the dividing wall having a height H1 and dividing the vessel into at least a first chamber and a second chamber, and (3) a molten metal pump in the vessel, preferably in the first chamber. The system may also include other devices and structures such as one or more of a ladle, an ingot mold, a launder, a rotary degasser, one or more additional pumps, and a pump control system.

The second chamber has a wall or opening with a height H2 that is lower than height H1 and the second chamber is juxtaposed another structure, such as a ladle or launder, into which it is desired to transfer molten metal from the vessel. The pump (either a transfer, circulation or gas-release pump) is submerged in the first chamber (preferably) and pumps molten metal from the first chamber past the dividing wall and into the second chamber causing the level of molten metal in the second chamber to rise. When the level of molten metal in the second chamber exceeds height H2, molten metal flows out of the second chamber and into another structure. If a circulation pump, which is most preferred, or a gas-release pump were utilized, the molten metal would be pumped through the pump discharge and through an opening in the dividing wall wherein the opening is preferably completely below the surface of the molten metal in the first chamber.

Therefore, the problems with splashing and the formation of dross in the ladle or launder are greatly reduced or eliminated by utilizing this system.

In addition, preferably the pump used to transfer molten metal from the first chamber to the second chamber is a circulation pump (most preferred) or gas-release pump, preferably a variable speed pump. When utilizing such a pump there is an opening in the dividing wall beneath the level of molten metal in the first chamber during normal operation. The pump discharge communicates with, and may be received partially or totally in the opening. When the pump is operated it pumps molten metal through the opening and into the second chamber thereby raising the level in the second chamber until the level surpasses H2 and flows out of the second chamber. This embodiment of a system according to

the invention eliminates the usage of a transfer pump and greatly reduces the problems associated therewith, such as dross formation, the formation of a solid plug of metal in the transfer pump riser or associated piping, and problems with tap-out holes.

Further, if the pump is a variable speed pump, which is preferred, a control system is used to speed or slow the pump, either manually or automatically, as the amount of molten metal in one or more structures varies. For example, if a system according to the invention is being used to fill a ladle, the amount of molten metal in the ladle can be determined by measuring the level or weight of molten metal in the ladle. When the level is relatively low, the control system could cause the pump to run at a relatively high speed to fill the ladle quickly and as the amount of molten metal increases, the pump control system could cause the pump to slow and finally to stop.

Utilizing such a variable speed circulation pump or gas-release pump further reduces the chance of splashing and formation or dross, and reduces the chance of lags in which there is no molten metal being transferred or that could cause a device, such as a ladle, to be over filled. It leads to even and controlled transfer of molten metal from the vessel into another device or structure.

Any device for measuring the amount of molten metal in a vessel, device or structure may be used, such as a float to measure the level, a scale to measure the weight, or a laser to measure the level.

It has also been discovered that by making the launder either level (i.e., at a 0° incline) or inclined backwards towards the vessel so that molten metal in the launder drains back into the vessel, the dross or skin that forms on the surface of the molten metal in the launder is not pulled away with the molten metal entering downstream vessels. Thus, this dross is less likely to contaminate any finished product, which is a substantial benefit. Preferably, a launder according to the inventor is formed at a horizontal angle leaning back towards the vessel of 0° to 10°, or 0° to 5°, or 0° to 3°, or 1° to 3°, or at a slope of about $\frac{1}{8}$ " for every 10' of launder.

BRIEF DESCRIPTION OF THE DRAWINGS

FIG. 1 is a top, perspective view of a system according to the invention, wherein a transfer chamber is included installed in a vessel designed to contain molten metal.

FIG. 2 is a top view of the system according to FIG. 1.

FIG. 3 is a side, partial cross-sectional view of the system of FIG. 1.

FIG. 4 is a top view of the system of FIG. 1 with the pump removed.

FIG. 5 is a side, partial cross-sectional view of the system of FIG. 4 taken along line B-B.

FIG. 6 is a cross-sectional view of the system of FIG. 4 taken along line C-C.

FIG. 7 is a top, perspective view of another system in accordance with the invention.

FIG. 8 is a top view of the system of FIG. 7 attached to or formed as part of a reverberatory furnace.

FIG. 9 is a partial, cross-sectional view of the system of FIG. 8.

FIG. 10 is a top view of an alternate system according to the invention.

FIG. 11 is a partial, cross-sectional view of the system of FIG. 10 taken along line A-A.

FIG. 12 is a partial, cross-sectional view of the system of FIG. 10 taken along line B-B.

FIG. 13 is a top view of a rotor according to the invention.

FIGS. 14 and 15 are side views of the rotor of FIG. 13.

FIGS. 16 and 17 are top, perspective views of the rotor of FIG. 13 at different, respective positions of the rotor.

FIG. 18 is a top view of the rotor of FIG. 13.

FIG. 19 is a cross-sectional view of the rotor of FIG. 18 taken along line A-A.

FIG. 20 is a side, partial cross-sectional view of an alternate embodiment of the invention.

FIG. 21 is a top, partial cross-sectional view of the embodiment of FIG. 20.

FIG. 22 is a partial, cross-sectional side view showing the height relationship between components of the embodiment of FIGS. 20-21.

DETAILED DESCRIPTION OF PREFERRED EMBODIMENTS

Turning now to the drawings, where the purpose is to describe a preferred embodiment of the invention and not to limit same, systems and devices according to the invention will be described.

The invention includes a transfer chamber used with a vessel for the purpose of transferring molten metal out of the vessel in a controlled fashion using a pump, rather than relying upon gravity. It also is more preferred than using a transfer pump having a standard riser tube (such as the transfer pumps disclosed in the Background section) because, among other things, the use of such pumps create turbulence that creates dross and the riser tube can become plugged with solid metal.

FIGS. 1-6 show one preferred embodiment of the invention. A system 1 comprises a vessel 2, a transfer chamber 50 and a pump 100. Vessel 2 can be any vessel that holds molten metal (depicted as molten metal bath B), and as shown in this embodiment is an intermediary holding vessel. Vessel 2 has a

first wall 3 and a second, opposite wall 4. Vessel 2 has support legs 5, inner side walls 6 and 7, inner end walls 6A and 7A, and an inner bottom surface 8. Vessel 2 further includes a cavity 10 that may be open at the top, as shown, or covered. An inlet 12 allows molten metal to flow into the cavity 10 and

molten metal flows out of the cavity 10 through outlet 14. At the top 16 of vessel 2, there are flat surfaces 18 that preferably have metal flanges 20 attached. A tap-out port 22 is positioned lower than inner bottom surface 8 and has a plug 22A that can be removed to permit molten metal to exit tap-out port 22. As shown, inner bottom surface 8 is angled downwards from inlet 12 to outlet 14, although it need not be angled in this manner.

A transfer chamber according to the invention is most preferably comprised of a high temperature, castable cement, with a high silicon carbide content, such as ones manufactured by AP Green or Harbison Walker, each of which are part of ANH Refractory, based at 400 Fairway Drive, Moon Township, Pa. 15108, or Allied Materials. The cement is of a type known by those skilled in the art, and is cast in a conventional manner known to those skilled in the art.

Transfer chamber 50 in this embodiment is formed with and includes end wall 7A of vessel 2, although it could be a separate structure built outside of vessel 2 and positioned into vessel 2. Wall 7A is made in suitable manner. It is made of refractory and can be made using wooden forms lined with Styrofoam and then pouring the uncured refractory (which is a type of concrete known to those skilled in the art) into the mold. The mold is then removed to leave the wall 7A. If Styrofoam remains attached to the wall, it will burn away when exposed to molten metal.

Transfer chamber 50 includes walls 7A, 52, 53 and 55, which define an enclosed, cylindrical (in this embodiment)

portion **54** that is sometimes referred to herein as an uptake section. Uptake section **54** has a first section **54A**, a narrower third section **54B** beneath section **54A**, and an even narrower second section **54C** beneath section **54B**. An opening **70** is in communication with area **10A** of cavity **10** of vessel **2**.

Pump **100** includes a motor **110** that is positioned on a platform or superstructure **112**. A drive shaft **114** connects motor **110** to rotor **500**. In this embodiment, drive shaft **114** includes a motor shaft (not shown) connected to a coupling **116** that is also connected to a rotor drive shaft **118**. Rotor drive shaft **118** is connected to rotor **500**, preferably by being threaded into a bore at the top of rotor **500** (which is described in more detail below).

Pump **100** is supported in this embodiment by a brackets, or support legs **150**. Preferably, each support leg **150** is attached by any suitable fastener to superstructure **112** and to sides **3** and **4** of vessel **2**, preferably by using fasteners that attach to flange **20**. It is preferred that if brackets or metal structures of any type are attached to a piece of refractory material used in any embodiment of the invention, that bosses be placed at the proper positions in the refractory when the refractory piece is cast. Fasteners, such as bolts, are then received in the bosses.

Rotor **500** is positioned in uptake section **54** preferably so there is a clearance of $\frac{1}{4}$ " or less between the outer perimeter of rotor **500** and the wall of uptake section **54**. As shown, rotor **500** is positioned in the lowermost second section **54C** of uptake section **54** and its bottom surface is approximately flush with opening **70**. Rotor **500** could be located anywhere where it would push molten metal from area **10A** upward into uptake section **54** with enough pressure for the molten metal to reach and pass through outlet **14**, thereby exiting vessel **2**. For example, rotor **500** could only partially located in uptake section **54** (with part of rotor **500** in area **10A**, or rotor **500** could be positioned higher in uptake section **54**, as long as it fit sufficiently to generate adequate pressure to move molten metal into outlet **14**.

Another embodiment of the invention is system **300** shown in FIGS. 7-12. In this embodiment a transfer chamber **320** is positioned adjacent a vessel, such as a reverberatory furnace **301**, for retaining molten metal.

System **300** includes a reverberatory furnace **302**, a charging well **304** and a well **306** for housing a circulation pump. In this embodiment, the reverberatory furnace **302** has a top covering **308** that includes three surfaces: first surface **308A**, second, angled surface **308B** and a third surface **308C** that is lower than surface **308A** and connected to surface **308A** by surface **308B**. The purpose of the top surface **308** is to retain the heat of molten metal bath **B**.

An opening **310** extends from reverberatory furnace **302** and is a main opening for adding large objects to the furnace or draining the furnace.

Transfer well **320**, in this embodiment, has three side walls **322**, **324** and **326**, and a top surface **328**. Transfer well **320** in this embodiment shares a common wall **330** with furnace **302**, although wall **330** is modified to create the interior of the transfer well **320**. Turning now to the inside structure of the transfer well **320**, it includes an intake section **332** that is in communication with a cavity **334** of reverberatory furnace **302**. Cavity **334** includes molten metal bath **B** when system **300** is in use, and the molten metal can flow through intake section **332** into transfer well **320**.

Intake section **332** leads to an enclosed section **336** that leads to an outlet **338** through which molten metal can exit transfer well **320** and move to another structure or vessel. Enclosed section **336** is preferably square, and fully enclosed except for an opening **340** at the bottom, which communi-

cates with intake section **332** and an opening **342** at the top of enclosed section **336**, which is above and partially includes the opening that forms outlet **338**.

In order to help form the interior structure of well **320**, wall **330** has an extended portion **330A** that forms part of the interior surface of intake section **332**. In this embodiment, opening **340** has a diameter, and a cross sectional area, smaller than the portion of enclosed section **336** above it. The cross-sectional area of enclosed section **336** may remain constant throughout, may gradually narrow to a smaller cross-sectional area at opening **340**, or there may be one or more intermediate portions of enclosed section **336** of varying diameters and/or cross-sectional areas.

A pump **400** has the same preferred structure as previously described pump **100**. Pump **400** has a motor **402**, a superstructure **404** that supports motor **402**, and a drive shaft **406** that includes a motor drive shaft **408** and a rotor drive shaft **410**. A rotor **500** is positioned in enclosed section **336**, preferably approximately flush with opening **340**. Where rotor **500** is positioned it is preferably $\frac{1}{4}$ " or less; or $\frac{1}{8}$ " or less, or $\frac{1}{16}$ " to 1", smaller in diameter than the inner diameter of the enclosed section **336** in which it is positioned in order to create enough pressure to move molten metal upwards.

A preferred rotor **500** is shown in FIGS. 13-19. Rotor **500** is designed to push molten metal upward into enclosed section **336**. The preferred rotor **500** has three identically formed blades **502**, **504** and **506**. Therefore, only one blade shall be described in detail. It will be recognized, however, that any suitable number of blades could be used or that another structure that pushes molten metal up the enclosed section could be utilized.

Blade **504** has a multi-stage blade section **504A** that includes a face **504F**. Face **504F** is multi-faceted and includes portions that work together to move molten metal upward into the uptake section.

A system according to the invention may also utilize a standard molten metal pump, such as a circulation or gas-release (also called a gas-injection) pump **20**. Pump **20** is preferably any type of circulation or gas-release pump. The structure of circulation and gas-release pumps is known to those skilled in the art and one preferred pump for use with the invention is called "The Mini," manufactured by Molten Metal Equipment Innovations, Inc. of Middlefield, Ohio 44062, although any suitable pump may be used. The pump **20** preferably has a superstructure **22**, a drive source **24** (which is most preferably an electric motor) mounted on the superstructure **22**, support posts **26**, a drive shaft **28**, and a pump base **30**. The support posts **26** connect the superstructure **22** a base **30** in order to support the superstructure **22**.

Drive shaft **28** preferably includes a motor drive shaft (not shown) that extends downward from the motor and that is preferably comprised of steel, a rotor drive shaft **32**, that is preferably comprised of graphite, or graphite coated with a ceramic, and a coupling (not shown) that connects the motor drive shaft to end **32B** of rotor drive shaft **32**.

The pump base **30** includes an inlet (not shown) at the top and/or bottom of the pump base, wherein the inlet is an opening that leads to a pump chamber (not shown), which is an cavity formed in the pump base. The pump chamber is connected to a tangential discharge, which is known in art, that leads to an outlet, which is an opening in the side wall **33** of the pump base. In the preferred embodiment, the side wall **33** of the pump base including the outlet has an extension **34** formed therein and the outlet is at the end of the extension.

In operation, the motor rotates the drive shaft, which rotates the rotor. As the rotor (also called an impeller) rotates,

11

it moves molten metal out of the pump chamber, through the discharge and through the outlet.

A circulation or transfer pump may be used to simply move molten metal in a vessel towards a transfer chamber according to the invention where the pump inside of the transfer chamber moves the molten metal up and into the outlet.

Alternatively, a circulation or gas-transfer **1001** pump may be used to drive molten metal out of vessel **2**. As shown in FIGS. 20-22, a system **1000** as an example, has a dividing wall **1004** that would separate vessel **2** into at least two chambers, a first chamber **1006** and a second chamber **1008**, and any suitable structure for this purpose may be used as dividing wall **1004**. As shown in this embodiment, dividing wall **1004** has an opening **1004A** and an optional overflow spillway **1004B**, which is a notch or cut out in the upper edge of dividing wall **1004**. Overflow spillway **1004B** is any structure suitable to allow molten metal (designated as **M**) to flow from second chamber **1008**, past dividing wall **1004**, and into first chamber **1006** and, if used, overflow spillway **1004B** may be positioned at any suitable location on wall **1004**. The purpose of optional overflow spillway **1004B** is to prevent molten metal from overflowing the second chamber **1008**, by allowing molten metal in second chamber **1008** to flow back into first chamber **1006** or vessel **2** or other vessel used with the invention.

At least part of dividing wall **1004** has a height **H1**, which is the height at which, if exceeded by molten metal in second chamber **1008**, molten metal flows past the portion of dividing wall **1004** at height **H1** and back into first chamber **1006** of vessel **2**. Overflow spillway **1004B** has a height **H1** and the rest of dividing wall **1004** has a height greater than **H1**. Alternatively, dividing wall **1004** may not have an overflow spillway, in which case all of dividing wall **1004** could have a height **H1**, or dividing wall **1004** may have an opening with a lower edge positioned at height **H1**, in which case molten metal could flow through the opening if the level of molten metal in second chamber **1008** exceeded **H1**. **H1** should exceed the highest level of molten metal in first chamber **1006** during normal operation.

Second chamber **1008** has a portion **1008A**, which has a height **H2**, wherein **H2** is less than **H1** (as can be best seen in FIG. 2A) so during normal operation molten metal pumped into second chamber **1008** flows past wall **1008A** and out of second chamber **1008** rather than flowing back over dividing wall **1004** and into first chamber **1006**.

Dividing wall **1004** may also have an opening **1004A** that is located at a depth such that opening **1004A** is submerged within the molten metal during normal usage, and opening **1004A** is preferably near or at the bottom of dividing wall **1004**. Opening **1004A** preferably has an area of between 6 in.² and 24 in.², but could be any suitable size.

Dividing wall **1004** may also include more than one opening between first chamber **1006** and second chamber **1008** and opening **1004A** (or the more than one opening) could be positioned at any suitable location(s) in dividing wall **1004** and be of any size(s) or shape(s) to enable molten metal to pass from first chamber **1006** into second chamber **1008**.

Optional launder **2000** (or any launder according to the invention) is any structure or device for transferring molten metal from a vessel such as vessel **2** or **302** to one or more structures, such as one or more ladles, molds (such as ingot molds) or other structures in which the molten metal is ultimately cast into a usable form, such as an ingot. Launder **2000** may be either an open or enclosed channel, trough or conduit and may be of any suitable dimension or length, such as one to four feet long, or as much as 100 feet long or longer. Launder **2000** may be completely horizontal or may slope

12

gently upward. Launder **2000** may have one or more taps (not shown), i.e., small openings stopped by removable plugs. Each tap, when unstopped, allows molten metal to flow through the tap into a ladle, ingot mold, or other structure. Launder **2000** may additionally or alternatively be serviced by robots or cast machines capable of removing molten metal **M** from launder **20**.

It is also preferred that the pump **1001** be positioned such that extension **31** of base **3000** is received in the first opening **1004A**. This can be accomplished by simply positioning the pump **1001** in the proper position. Further the pump may be held in position by a bracket or clamp that holds the pump against the dividing wall **1004**, and any suitable device may be used. For example, a piece of angle iron with holes formed in it may be aligned with a piece of angle iron with holes in it on the dividing wall **1004**, and bolts could be placed through the holes to maintain the position of the pump **1001** relative to the dividing wall **1004**.

In operation, when the motor is activated, molten metal is pumped out of the outlet through first opening **1004A**, and into chamber **1008**. Chamber **1008** fills with molten metal until it moves out of the vessel through the outlet. At that point, the molten metal may enter a launder or another vessel.

If the molten metal enters a launder, the launder preferably has a horizontal angle of 0° or is angled back towards chamber **1008** of the vessel **2**. The purpose of using a launder with a 0° slope or that is angled back towards the vessel is because as molten metal flows through the launder, the surface of the molten metal exposed to the air oxidizes and dross is formed on the surface, usually in the form of a semi-solid or solid skin on the surface of the molten metal. If the launder slopes downward it allows gravity to influence the flow of molten metal, and tends to pull the dross or skin with the flow. Thus, the dross, which includes contaminants, is included in downstream vessels and adds contaminants to finished products.

It has been discovered that if the launder is at a 0° or horizontal angle tilting back towards the vessel, the dross remains as a skin on the surface of the molten metal and is not pulled into downstream vessels to contaminate the molten metal inside of them. The preferred horizontal angle of any launder connected to a vessel according to aspects of the invention is one that is at 0° or slopes (or tilts) back towards the vessel and is between 0° and 10°, or 0° and 5°, or 0° and 3°, or 1° and 3°, or a backward slope of about 1/8" for every 10" of launder length.

Having thus described some embodiments of the invention, other variations and embodiments that do not depart from the spirit of the invention will become apparent to those skilled in the art. The scope of the present invention is thus not limited to any particular embodiment, but is instead set forth in the appended claims and the legal equivalents thereof. Unless expressly stated in the written description or claims, the steps of any method recited in the claims may be performed in any order capable of yielding the desired result.

What is claimed is:

1. A vessel for use in a system for transferring molten metal, the vessel including (a) a first end through which molten metal enters, (b) a second end through which molten metal exits, (c) a cavity, (d) a transfer chamber with an open top; an opening in communication with the cavity; an uptake section above and in communication with the opening; and an outlet above the opening, the outlet in communication with the uptake section and; (e) a launder in communication with the outlet and in communication with a second vessel, wherein the second vessel is separate from the first vessel and does not share a common wall with the first vessel.

13

2. The vessel of claim 1 that also includes an inner bottom surface that slopes downward towards the opening.
3. The vessel of claim 1 that further includes a tap-out opening positioned in the vessel wherein the transfer chamber is located lower than the opening.
4. The vessel of claim 1 wherein the outlet is at least two feet above the opening.
5. The vessel of claim 2 wherein the outlet is at least two feet above the inner bottom surface.
6. A transfer chamber system for use with a vessel including a cavity for containing molten metal, the transfer chamber system being in fluid communication with the vessel cavity and including:
- (a) an open top through which a molten metal pump is received;
  - (b) an inlet in communication with the cavity to permit molten metal to enter the transfer chamber;
  - (c) an enclosed inner section and an open section, the enclosed inner section having a first opening in communication with the open section;
  - (d) the molten metal pump positioned in the transfer chamber, the pump having a motor, a drive shaft having a first end connected to the motor, and a second end, and a rotor connected to the second end, wherein the shaft is positioned at least partially in the enclosed inner section and the rotor is positioned at least partially in the enclosed inner section;
  - (e) an outlet above the first opening and below the motor, wherein molten metal can exit the transfer chamber through the outlet;
  - (f) wherein the rotor has a diameter, and the enclosed inner section has an interior diameter, and the interior diameter is between $\frac{1}{8}$ " to 1" greater than the diameter of the rotor;
- wherein, as the pump operates the rotor is rotated and directs molten metal up into the enclosed inner section and out of the outlet.
7. The transfer chamber system of claim 6 that has a bottom surface two feet or less beneath the first opening.
8. The transfer chamber system of claim 6 wherein the pump does not include a pump base housing the rotor.
9. The transfer chamber system of claim 6 wherein the pump does not include a superstructure or support posts.

14

10. The transfer chamber system of claim 6 wherein the drive shaft comprises a motor shaft coupled to a rotor shaft and the rotor shaft is positioned at least partially in the enclosed inner section.
11. The transfer chamber system of claim 10 wherein the rotor shaft is comprised of one or more of the group consisting of graphite and ceramic.
12. The transfer chamber system of claim 6 that has three walls and shares a fourth, common wall with the vessel.
13. The transfer chamber system of claim 6 wherein the pump is supported by a carriage connected to the transfer well.
14. The transfer chamber system of claim 6 wherein the transfer chamber has a first section having a first cross-sectional area and a second section having a second cross-sectional area, the second section adjacent the opening and the second cross-sectional area being smaller than the first cross-sectional area.
15. The transfer chamber system of claim 14 that has a third section having a third cross-sectional area, the third section being between the first section and the second section, and the third cross-sectional area being smaller than the first cross-sectional area, but larger than the second cross-sectional area.
16. The vessel of claim 1 wherein a launder is connected to the outlet.
17. The transfer chamber system of claim 12 wherein a launder is connected to the outlet and the launder has a horizontal angle of between 0° and 10° tilting back towards the outlet.
18. The transfer chamber system of claim 12 wherein the launder has a horizontal angle of between 0° and 5° tilting back towards the outlet.
19. The transfer chamber system of claim 12 wherein the launder has a horizontal angle of between 0° and 3° tilting back towards the outlet.
20. The transfer chamber system of claim 12 wherein the launder has a horizontal angle of between 1° and 3° .
21. The transfer chamber system of claim 12 wherein a launder is connected to the outlet and the launder is angled backwards towards the outlet at a downward slope of $\frac{1}{8}$ " for every 10" of launder length.
22. The transfer chamber system of claim 12 that further includes a tap-out opening positioned lower than the opening.
